JAMES A. POWELL, OF INTERVILLA, PENNSYLVANIA, ASSIGNOR TO FOSTER WHEELER CORPORATION, OF NEW YORK, N. Y., A CORPORATION OF NEW YORK

STEAM-POWER PLANT

Application filed May 14, 1929. Serial No. 362,887.

My invention relates to steam power plants and particularly to steam power plants having a plurality of prime movers operating within different ranges of steam pressure.

For high efficiency, it is desirable that steam of high superheat be supplied to high pressure prime movers. It is also desirable to superheat the steam passing from a high pressure prime mover to a low pressure prime mover. This is often done by passing the inter-stage steam through reheaters, for example a steam heated reheat and a flue gas heated reheat arranged in series.

If a high pressure prime mover is bypassed so that steam passes direct to a low pressure prime mover, the superheated steam may be too hot for the flue gas reheat. Not alone is such steam of the superheat of the source but the necessary throttling in the by-pass adds heat of superheat. Consequently it is advisable to desuperheat the by-passed steam before its passage through the flue gas heated reheat. The flue gas heated reheat cannot or should not be bypassed because it is likely to burn out.

In steam power plants of this type, feed water is usually heated by steam. This is accomplished in the final stage before the flue gas feed heater by what is known as a closed heater, as distinguished from a thoroughfare heater. A thoroughfare heater is one in which steam as steam passes through the heater while a closed heater is one in which the heating steam is condensed.

I propose to give such closed heater a double function by using it merely as a feed heater during normal operation and using it as a desuperheater when the high pressure prime mover is by-passed by passing the by-passed steam through it on its way to the re-heaters and thus cooling the by-passed steam sufficiently to prevent excessively high temperature in the gas reheat. By this means I obtain the desired and necessary conditions for the steam with a minimum of steam plant equipment.

The invention is illustrated by means of the accompanying drawing showing a steam power plant embodying the invention.

On the drawing, reference character 10 designates a boiler which may be of any of various types, suitably heated and having a superheater 11 for superheating the steam after the disengagement of the steam from the water in the boiler proper. A flue 12 leads from the boiler and encloses a flue gas heated reheat or gas reheat 13 and a feed water heater 14. Boiler feed water is pumped through feed line 16 into the feed water heater and from the feed water heater into the boiler through connection 17.

Boiler steam passes through conduit 18 to a high pressure prime mover, illustrated as a turbine 19. The turbine may drive an electric generator 20. Exhaust steam from turbine 19 passes through conduit 21 and can pass through conduit 22 or through conduits 23 and 24 and passes through conduit 25 into a steam heated reheat 26. Thence the steam passes through conduit 27, through reheat 13 and through conduit 28 to a low pressure prime mover 29, also illustrated as a turbine. Turbine 29 may drive an electric generator 30. Generators 20 and 30 may be connected to the same electric circuit. Instead of two separate turbines, the high and low pressure prime movers may be different sections of a single turbine or other motor connected to drive a single electric generator or other power consumer. Steam flow through the turbines may be controlled in a number of ways. One way is by a centrifugal governor operated from the shaft of either turbine and arranged to control a supply valve 31 for the high pressure turbine.

Conduits 23 and 24 connect with the steam chamber 32 of a feed water heater 33. Feed water is supplied to the feed water heater by pump 34 and through conduit 35. The water circulates through tubes 37 within the feed water heater and is heated by the steam. Thence the feed water passes through conduit 38 and through pump 39 into conduit 16. Condensate is withdrawn from the feed water heater by pump 39 and forced into conduit 38.

In conduit 22 is a valve 40. In conduit 23 is a valve 41. In conduit 24 is a valve

42. Between conduit 18 and conduit 21 extends a by-pass conduit 43 in which is a valve 44. Between conduit 21 and conduit 23 is a connection 45 having a valve 46 therein. Conduit 21 has a check valve 47 therein between the turbine and the connection with conduit 21 of by-pass conduit 43 therewith. This check valve is such as to prevent steam from passing through conduit 43 and back through conduit 21 into the high pressure turbine exhaust opening.

10 Steam for heater 26 is taken from the boiler, passes through conduit 49 and into a part 50 of the re heater. The steam is condensed 15 and the condensate passes by gravity through conduit 51 back to the boiler.

During normal operation, the main path 20 of flow of steam is through superheater 11, through conduit 18, through high pressure prime mover 19, through conduit 21, through conduit 22, through conduit 25, through re heater 26, through conduit 27, through re heater 13, through conduit 28 and through low pressure prime mover 29 into the condenser. Condensate from the condenser 25 passes back to the boiler as feed water. The feed water is heated in feed water heater 33 by steam which is tapped or bled from the main path of steam flow through conduit 45. This steam passes through conduit 30 32 into space 32 of the feed water heater where it is condensed as it heats the feed water in tubes 37. The amount of this steam, for heating the feed water in heater 33 is 35 small compared to the amount of steam passing in the main path of flow. Consequently conduit 45 can be of small size compared to the diameter of the conduits forming the main path of flow. The condensed steam is returned by pump 39 to the boiler.

40 When the high pressure prime mover is by-passed, the main path of flow is from superheater 11, through conduit 18, by-pass conduit 43, through the part of conduit 21 45 between conduit 43 and conduit 23, through conduit 23, through space 32 of heater 33, through conduit 24, through conduit 25 and thence on to the low pressure prime mover as in the case of normal operation. By-pass conduit 43 is of a size to take the amount 50 of steam flow of the main path. The feed water is heated by the main path flow in this case and the main path steam is de-superheated by the feed water. By this 55 means the steam, which is highly superheated as a result of the original superheating and the throttling through the valve or valves in the by-pass 43 is reduced in temperature so as not to permit excessive temperature in the flue gas heated re heater 13.

60 In a plant in which the high pressure prime mover is by-passed at times of decrease of load as in a plant using a steam accumulator connected in parallel with the high pressure prime mover which is charged

during light load and which delivers steam for power or other purposes during heavy load, it may be desirable to control valves 40, 41, 42, 44 and 46 automatically. Valve 44 may be connected to the centrifugal governor for the turbine or turbines so that it opens when the speed exceeds a given value and mechanism may be provided whereby, when valve 44 is opened, valves 40 and 46 are automatically closed and valves 41 and 42 automatically opened. For this purpose servo-motors for the various valves can be connected to a common relay controlled by the speed of the turbine, or such an arrangement may be controlled from pressure in the steam supply line. In case of manual regulation, mechanism may be provided inter-connecting the valves to operate to change the steam flow as above described when by-pass valve 44 is opened.

80 While I have shown a separate connection 45 for bleeding steam to be condensed in the feed heater, this connection may be dispensed with in which case valve 41 takes over the function of valve 44.

85 The heater may be provided with a vent for initiating circulation of steam there-through and other supplemental devices customary to plant equipment of this type.

90 It will be understood that wide variations of plant layout are possible within the scope of the invention.

95 What I claim is:

1. That improvement in the operation of steam plants including a high pressure prime mover, a low pressure prime mover and a feed water heater and having a main path of steam flow including the high pressure and low pressure prime movers and a by-pass path of flow around the high pressure prime mover which comprises withdrawing steam from said main path of flow to heat feed water in the feed water heater and thereby condensing the withdrawn steam and desuperheating the by-passed steam in the feed water heater by the cooling effect of feed water without condensing the by-passed steam.

100 2. A steam plant comprising a source of steam, a high pressure motor, a low pressure motor, a feed water heater, means for conducting feed water through the feed water heater, means for conducting steam from said source past the high pressure motor through the feed water heater and to the low pressure motor and for conducting steam from the high pressure motor into the feed water heater and means to withdraw condensed steam from the feed water heater.

105 3. A steam plant comprising a source of steam, a high pressure motor, a low pressure motor, a feed water heater, means for conducting feed water through the feed water heater, a conduit for conducting steam
